[57] **CLAIM**

I claim the new, original ornamental design for the jeweled ball string necklace, as shown in the drawings and described.

DESCRIPTION

FIG. 1 is a front plan view of the jeweled ball string necklace of the present invention;

FIG. 2 is a side plan view of the jeweled ball string necklace of FIG. 1;

FIG. 3 is an enlarged top view of the jeweled ball of the jeweled ball string necklace of FIG. 1; and,

FIG. 4 is an enlarged bottom view of the terminal balls of the string and jeweled ball of the jeweled ball string necklace of FIG. 1.
